UNITED STATES PATENT OFFICE.

CHARLES HARBAUGH AND CLARENCE C. BROSUS, OF JOHNSTOWN, PENNSYLVANIA.

RAILROAD-TIE.

1,158,919.

Specification of Letters Patent.

Patented Nov. 2, 1915.

Application filed January 23, 1915. Serial No. 3,936.

To all whom it may concern:

Be it known that we, CHARLES HARBAUGH and CLARENCE C. BROSUS, citizens of the United States, residing at Johnstown, in the 5 county of Cambria and State of Pennsylvania, have invented certain new and useful Improvements in Railroad-Ties; and we do hereby declare the following to be a full, clear, and exact description of the invention, 10 such as will enable others skilled in the art to which it appertains to make and use the same, reference being had to the accompanying drawings, and to letters or figures of reference marked thereon, which form a 15 part of this specification.

This invention relates to improvements in railroad ties, and means associated therewith for fastening a rail in position.

One of the objects of the invention is to 20 provide a resilient metal tie to provide the qualities inherent in wood ties.

A further object of our invention is to provide a simple and inexpensive metal tie having means for resisting lateral movement 25 of the rails.

Another object of the invention is to provide simple and durable means for holding the rails in conjunction with a resilient metal tie.

30 Other objects and advantages will be hereinafter pointed out and particularly referred to in the claims.

In the accompanying drawing:—Figure 1 is a perspective view showing the application 35 of the invention. Fig. 2 represents views of the two clamp members. Fig. 3 is a detail longitudinal section of the tie, and the rail in position. Fig. 4 is a cross section through one of the members on the line $\alpha-\alpha$ 40 of Fig. 3. Fig. 5 is a detail view of a slightly different form of the invention.

1 indicates a metal tie which is substantially flat and of suitable thickness, the opposite ends being inclined downwardly and outwardly, as shown at 2, to provide a convenient means for anchoring the tie. Near 45 adjacent ends of the tie are offset portions 3, and in the upper surfaces of these offset portions are depressions 4, to receive the rails 5.

50 The means employed to clamp the rails comprise two coöperating members 8 and 9, similarly constructed; consequently but one will be described.

Each member comprises an upper plate 55 10, formed on its inner free end with a flange 11, which corresponds to the contour or the

side of the rail, and fits snugly thereagainst as shown in the drawing. The flange 11, extends below the plane of the bottom surface of the upper plate 10, as shown at 12, 60 and engages one of the side walls 13, of the depression 4, which prevents the clamp member moving laterally in a direction away from the adjacent side of the rail.

Extending laterally and downwardly 65 from the side of the top plate 10, is a vertical connecting portion or side plate 15, and extending inwardly therefrom, parallel to the upper plate 10, and engaging the under surface of the tie 1, is a bottom plate 16. 70 The upper and lower plates 10 and 16, and the side plate 15, embrace the upper and lower surfaces, and one side of the tie when the parts are assembled. In the upper and lower plates 10 and 16, are alined bolt openings 18, and in the tie are corresponding openings 18', which may be slightly elongated, and through these openings pass bolts 20, to clamp the member to the tie. Extending laterally through the flange 11, on the 75 end of the member, are openings 21, which are in alinement with similar openings 21^a, formed in the ends of the rails, and through these openings extend transverse bolts 22, which lock the members in operative position. 85

When the parts are assembled as shown in Fig. 1, the depending flange portions 12, on the respective members 8 and 9, engage the opposite walls 13, of the depressions 4, 90 formed in the tie, and the respective side plates 15, of the two members engage opposite side edges of the tie, on opposite sides of the rails, which with the bolts, effectually prevent longitudinal displacement of the 95 members with reference to the tie and the rails. In addition to this clamping action of the bolts 20, the bolts 12, which pass through the flanges 11, and the rails, lock the rails to the members 8 and 9, so that by 100 the construction shown and described, lateral or end play of the rails is absolutely prevented, for obviously because of the flanges 11, engaging the walls of the rails, and the walls of the depressions, as well as 105 the flange of the rails engaging the walls 13, and because of the side portions of the members being located as shown, any movement of the parts, once the bolts are tightened, is absolutely prohibited. 110

By constructing the members 8 and 9 to engage opposite edges of the tie, on opposite

sides of a rail, an important result is accomplished; that is to say, if the bolts should become worn and break off, and the members slip on the tie, they will tend to bind between the rail and the walls 13, of the depressions, hence the ends of the rails will be held together.

The relative thickness of the tie and its length, renders the tie substantially resilient, consequently the pounding of the rolling stock on the rails is relieved by the tie yielding, which constitutes one of the essential features of a tie of wooden construction.

Of course, it is to be understood that the respective parts are so fitted as to provide for expansion and contraction, and that the length of the tie, and the fact that it is substantially flat throughout its length between the rails, affords a convenient means for adding resiliency to the structure.

In Fig. 5, the flat tie is formed with depending flanges 30, to strengthen the structure.

What we claim is:—

1. The combination of a metal tie formed with depressions near its ends, rail clamps comprising two members, each member comprising a flanged end which engages the outer surfaces of a rail, the bottom of the flange engaging a wall of the depression in the tie, each member having an upper and lower plate connected by an end portion to embrace the upper and lower surfaces of the tie, and bolts for securing the clamps to the tie.

2. The combination of a flat metal railroad tie formed with depressions near its ends, two clamp members, each of which is formed with end flanges which engage the sides of the rails and which are formed with openings, bolts extending through the openings to clamp the rails, each member having an upper plate and a lower plate connected at one side with an end plate, the end plates of the two members being disposed on opposite sides of the tie on opposite sides of the rail, and bolts passing through the members to secure same to the tie.

3. The combination of a metal tie formed with depending portions, the upper surfaces of the depending portions having depressions, rail clamps comprising two members, each member having portions which engage the side of rails and one wall of a depression,

each said member having a plate engaging the under surface of the tie and abutting against the wall of one of the depending portions.

4. The combination of a metal tie formed with depressions and depending portions below the depressions, rail clamps comprising two members, each member comprising a flanged end which engages the outer surface of a rail, the bottom of the flange engaging a wall of the depression in the tie, each member having an upper and lower plate connected by an end portion to embrace the upper and lower surfaces of the tie, the lower plates of adjacent clamp members engaging the outer walls of the depending portion below the depressions, and bolts for securing the members together.

5. The combination of a metal tie formed with depressions and depending portions below the depressions, rail clamps comprising two members, each member comprising a flanged end which engages the outer surface of a rail, the bottom of the flange engaging a wall of the depression in the tie, each member having an upper and lower plate connected by an end portion to embrace the upper and lower surfaces of the tie, the end portions of the two clamp members being disposed on opposite sides of the tie on opposite sides of the rail and embracing the edges of the tie, the lower plates of adjacent clamp members engaging the outer walls of the depending portion below the depression, and bolts for securing the members together.

6. The combination of a metal tie having depending portions near its ends, the upper surfaces of the depending portions having depressions, rail clamps comprising two members, each member having a portion which abuts against the rail, and a plate which lies under the tie and engages against the edge wall of one of the depending portions, and means for securing the clamps to the tie.

In testimony whereof we have signed our names to this specification in the presence of two subscribing witnesses.

CHARLES HARBAUGH.
C. C. BROSIUS.
